INVENTOR

C. S. Sherwood Jr.

UNITED STATES PATENT OFFICE.

CALDER S. SHERWOOD, JR., OF PORTSMOUTH, VIRGINIA.

DESIGN FOR A BADGE.

No. 38,218.

Specification for Design.

Patented Sept. 4, 1906.

Application filed May 21, 1906. Serial No. 318,111. Term of patent 8½ years.

To all whom it may concern:

Be it known that I, CALDER SMITH SHERWOOD, Jr., a citizen of the United States, residing at Portsmouth, in the county of Norfolk and State of Virginia, have invented a new, original, and ornamental Design for Badges, of which the following is a specification, reference being had to the accompanying drawing, forming a part thereof.

The figure is a plan view showing the design of the badge.

I claim—

The ornamental design for a badge, as shown.

C. S. SHERWOOD, JR.
